UNITED STATES PATENT OFFICE.

EDWIN R. GILL, OF YONKERS, NEW YORK.

FRICITION BAND.

Application filed May 7, 1923. Serial No. 637,107.

To all whom it may concern:

Be it known that I, EDWIN R. GILL, a citizen of the United States, and a resident of Yonkers, Westchester County, State of New York, have invented a certain Improvement in Friction Bands, of which the following is a specification.

The present invention relates to an improved construction for use in any form of mechanism depending upon frictional resistance for its operation. The principles underlying the invention are capable of embodiment in an indefinite number of forms, and particularly in friction clutches whether flat faced or of the drum type. In a preferred form, the improvement is particularly adapted for use in "speed bands" on motor cars, whether applied to the brake or to the control of the clutches governing the speed changing or stopping and starting means. Where used in frictional clutches or brakes of the drum type, the invention may be employed either upon the concave surface of an external clutch band or the convex surface of an internal clutch band.

The valuable properties of cork when used to create friction are well known, and more or less successful attempts have been made to utilize groups of cork masses for this purpose in a commercially satisfactory manner. The present invention supplies means for carrying out this end in such a manner as to overcome certain well recognized difficulties which have heretofore been met with in this field. The invention also covers the use of any friction-producing masses which may be suitable as substitutes for cork.

In employing cork, or its equivalent, in the production of a friction-producing surface, the cork is often used in the form of a number of masses held in cavities or perforations in a foundation of brass or other suitable metal. One difficulty that has been encountered in these cases is that of securing the masses firmly in place. One principal object of the present invention is the successful solution of this problem.

Another object of the invention is the production of means whereby the foundation to which the cork masses are applied may be perforated and prepared to receive the cork as quickly and cheaply as possible, and without danger of weakening or otherwise injuring it. In carrying out my invention, I am able to punch out all of the perfora-

tions at once, by a single forward movement of a group of dies.

In order to make such an operation as this possible, it is clear that the foundation plate must be quite thin, and indeed, I have successfully used a foundation plate only a sixteenth of an inch thick for this purpose. It is clear that a sheet of brass as thin as this would not serve to hold the cork masses securely, if the latter were merely driven into the perforations. The area of contact between cork and brass would not be sufficient to produce the necessary holding friction under conditions of use. Moreover a thin band of this character, used by itself, would not be strong enough to meet the conditions of practical use.

Accordingly my present invention comprises a composite foundation structure, wherein a number of relatively thin metal strips are used in a manner to re-enforce each other. The strip occupying the working face of the foundation or band should be made of suitable friction metal, preferably brass. Behind this is employed a similar strip of iron; and the couple thus formed is preferably secured to an exterior strip of steel or other resilient metal. This last is only perforated where it is riveted to what may be called the cork-holding couple of friction metal and iron or the like.

In order to provide a perfectly secure fastening for the cork masses, consistently with the use of thin brass plates; the middle, or iron, plate or strip is provided with perforations registering with those in the brass strip, but made somewhat larger than these last. The cork masses are made of such a size as to require forcing into the perforations in the inner or brass plate, and are of a size to project into the perforations in the middle or iron plate, while also projecting above the free surface of the brass plate. The portions of the cork masses which have been thus forced through the brass plate swell as soon as they enter the larger perforations in the iron plate, and the swollen portion effectually prevents the masses from coming out of the seats or sockets thus provided.

In addition to facilitating quick and cheap manufacture, the use of thin plates has a further advantage where bands are used on friction drums. In order to place such bands in position when assembling the mechanism, they have to be opened to an ab-

normal extent to make it possible to pass them over their cylinders. If thick plates are used, they are liable to take on a "set" or a permanent molecular displacement. This interferes with proper fitting and impairs their resilience. This effect is reduced to a minimum with thin plates. Where thin plates are used the dies also last much longer than when used on thick plates.

10 It is a conspicuous advantage of this invention that it makes it possible to use friction-producing masses that are relatively small transversely thus increasing the total active area available. At the same time, as the depth of each mass is great in proportion to its width, the danger of accidentally forcing masses out of place is decreased.

15 In the accompanying drawings, Figure 1 is a side elevation of a preferred form of 20 spring friction band of a type useful as a "speed band" for automobiles, the same being shown in its normal, uncompressed or idle condition, Figure 2 is a greatly exaggerated view in section of a small portion of 25 a composite foundation in flat position, Figure 3 is a perspective view of a cork mass as used in the improved structure, the same being shown greatly enlarged, Figures 4 to 6 inclusive are enlarged views of portions 30 of the outer or steel band, the middle or iron band, and the inner or brass band or strip respectively, all shown in flat position, Figure 7 is a similar view of these portions superposed in the flat and before being bent 35 into final form and riveted together, and Figure 8 is a view in elevation of one form of clutch operating mechanism illustrated by way of example.

40 In Figure 1 the speed band or brake band shown is one adapted to be used in controlling the movement of a revolving drum, and it is there shown substantially in the "normal" position, by which is meant the position which it naturally assumes when 45 free, and to which it tends to return by its own resilience.

45 As shown in this figure, the band comprises three concentric strips, placed one over the other and secured together. The 50 outermost or supporting strip 10 is made of resilient metal such as steel, the ends of which are preferably supplied with ears 11 and 12, of a well known character, serving for the attachment of mechanism of any 55 suitable character whereby the entire band may be more or less tightened upon the revolving drum to be controlled.

60 The "cork holding couple", composed of an interior strip 13 and a middle strip 14, 65 is secured to the supporting strip 10 by rivets 15 passing through all these strips at suitable intervals. The effective frictional grip is secured by cork masses 16 or their equivalents, preferably cylindrical in form, 70 as shown in Figure 3, which are secured in

place as hereinafter described. It is to be understood that these masses may be of any convenient shape without departing from the invention.

75 The method or process employed in the preparation of the various strips composing the entire band is illustrated in Figures 4 to 7 inclusive. In these figures of drawing, interior strips are shown provided with three longitudinal rows of circular holes, 80 which have been found convenient in practice. Obviously the invention is not limited to this particular arrangement or shape of perforations.

85 In preparing templates for constructing dies adapted to punch out an entire strip in one operation, the full length of each strip may be considered for the present purpose, as composed of substantially similar sections 90 between the successive rivet holes 17 and 18 in the outermost plate 10.

95 Since the various strips are separately punched while in the flat, it is clear that the exact location of the perforations, intended to register when the device is in the 100 normal curved position shown in Figure 1, must be laid out with due respect to the change in their relative positions caused by bending them into such normal position. Figures 4 to 7 illustrate the method employed on a scale that is greatly exaggerated, to make the same clearer to the eye.

105 In preparing the guiding templates, similar sections of which are shown in these 110 figures, the position of riveting holes are 100 first accurately ascertained on all three strips while in the normal curved position. When the strip templates are then straightened and the flat strips are compared with 115 end holes at one end of all three coinciding, the positions of the other rivet holes will be found to be out of registry to a progressively greater extent, measuring away from the coinciding holes. This is 120 illustrated for the first section in Figures 110 4 to 7 wherein the hole 17 in the steel plate 10 (Figure 4) coincides with the dotted circle 17^a in the middle or iron strip 14 (Figure 5) and the hole 17^b in the brass strip 13 (Figure 6); while at the opposite 125 end of the first section, the dotted circle 18^a in the strip 14 and the circle 18^b in the strip 15 represent the positions of the holes through which the next rivet passes.

130 As there shown the distance from 17^a to 18^a is shorter than from 17 to 18, and the distance from 17^b to 18^b is still shorter. This is due to the fact that the total length of the strip 14 is somewhat less when straightened out than that of the strip 10, and that the strip 13 is correspondingly shorter than the strip 14.

135 The respective positions of the rivet holes in the three strips being known, the next step is to lay out the middle row of perfo-

5 rations 19 in the middle or iron strip 14, so that a perforation at one end of the section shall be concentric with the position 17^a and another at the opposite end of the 10 section shall be concentric with the position 18^a; and that the intermediate perforations, all of the same size, shall be equally spaced. This being done, the other two rows of perforations, 20 and 21, are similarly laid out, 15 taking care that the transverse lines joining the centers of perforations in the two side rows shall cross the line of centers of the middle row half way between centers. The ideal hexagonal arrangement of perforations is thus attained in the middle strip 14, and the maximum proportion of cork area is secured.

20 The same procedure can then be followed with respect to the innermost, or brass, strip 13 (Figure 6) taking care that the longitudinal lines of centers of the three rows in the strip 13 are the same distance apart as those in the strip 14. The distances apart measured longitudinally between the 25 centers of perforations 22, 23 and 24 respectively on the innermost strip 13, will, however, be less than that between corresponding centers on the middle strip 14. The perforations on the strip 13 are also 30 somewhat smaller than those in the strip 14 for the reasons already explained.

35 When the three templates have been thus prepared, their appearance as superposed flat, with the brass plate 13 next the observer will be as illustrated on an exaggerated scale in Figure 7. When bent into the "normal" form shown in Figure 1, however, the centers of all holes will be in substantial registry. Accordingly if strips be 40 punched from dies made according to such templates, they can be riveted together in the manner shown in Figures 1 and 2, and the inner "cork holding" couple will present rows of openings in the friction plate 45 13, each of which is backed up by a concentric opening made somewhat larger in the middle or iron plate 14. When the cork masses 16 are forced through the friction plate 13, they will swell out within 50 the enlarged space afforded by the openings in the iron plate, being thus secured from accidental removal. This is plainly shown on an exaggerated scale in Figure 2.

55 In this figure is also shown a preferred detail of construction, namely the cupping or swaging inward of the brass or friction plate 13 around the rivet holes, as shown at 25. The conical projection thus formed fits into the corresponding large perforations 60 (of normal size) in the middle plate 14. By this expedient perfect coincidence of perforations is assured for each section separately, and any tendency of the middle strip 14 to "creep" is counteracted.

65 While the principles of construction here-

in described, may be embodied in a great variety of forms of friction clutch, well known or otherwise, it is sufficient to show one simple form of clutch operator for the particular type of apparatus shown in Figure 1. Such an operator is illustrated in Figure 8, wherein the friction band as a whole is shown at 26, surrounding a drum 27, whose movement it controls.

70 The tightening and loosening of the band are carried out by means attached to the ears 28 and 29, corresponding to the ears 12 in Figure 1. A spring 30 between these ears is preferably supplied which tends to force them apart.

75 An operating shaft 31 has one end secured to the ear 29 and extends through the other ear 28 and then through a stationary bearing 32, having its other end provided with a fixed collar 33. Between this collar and the face of the bearing 32 is located the base of a lever 34 which turns loosely on the shaft 31. This lever may have a 80 pedal at its end for operation, as shown, or may be otherwise operated.

85 The ear 28 is held stationary by an extension sleeve 35 abutting upon the bearing 32. The outer face of this bearing has a curved cam surface 36, into which fits the cam surface 37 on the base of the lever. 90 Upon swinging the lever, the cams act to force its base outward against the collar 33, causing the shaft 31 to slide to the left, thus bringing together the ears 28 and 29, and 95 tightening the band.

100 Return movement of the lever, restores the position shown in Figure 8, and allows the spring 30 to separate the ears and loosen the band.

105 Various changes may be made in this apparatus without departing from the scope of this invention, which is not limited to the details herein shown and described.

What is claimed is—

110 1. In apparatus for the purpose described, a perforated friction strip, a backing strip applied behind said friction strip and having perforations somewhat larger than those in the friction strip and registering therewith, and friction producing masses forced through said perforations and allowed to swell behind them.

115 2. A foundation for supporting friction producing masses comprising a friction strip and a backing strip applied behind the same, said strips having registering perforations which are larger in the backing strip than in the friction strip.

120 3. A compound friction band comprising a plurality of thin metal strips secured together, one at least of which is resilient, and friction-producing masses forced into the working face of the band and projecting above its surface.

125 4. In apparatus as in claim 3, an inner

strip of friction-metal, a middle strip and an outer strip of resilient metal.

5. In a compound friction band, an outer strip of resilient metal, an inner perforated strip secured parallel thereto, and means between said strips for holding them apart while leaving a free space behind the perforations in the inner strip.

6. In a compound friction band, an outer strip of resilient metal, an inner perforated strip, an intermediate perforated strip into some of the perforations of which portions of the inner strip project, and rivets securing the three strips together and passing through said last named perforations.

7. In a compound friction band, a fric-

tion strip, a backing strip secured behind the same and rivets passing through both, the edges of the rivet holes in the friction strip being swaged inward to form a concave portion fitting the corresponding hole in the backing strip.

8. As mechanical elements for use in assembling a compound friction band, two thin flat metal strips having rows of perforations set at equal distances apart laterally, the perforations in one strip being slightly further apart longitudinally than in the other strip.

In testimony whereof I have hereto set my hand on this 4th day of May, 1923.

EDWIN R. GILL.
